(57) **CLAIM**

The ornamental design for a curved object holder, as shown and described.

DESCRIPTION

FIG. 1 is a front view of a curved object holder in accordance with the present invention;

FIG. 2 is a back view of the curved object holder in accordance with the present invention;

FIG. 3 is a top view of the curved object holder in accordance with the present invention;

FIG. 4 is a bottom view of the curved object holder in accordance with the present invention;

FIG. 5 is a left-side view of the curved object holder in accordance with the present invention;

FIG. 6 is a right-side view of the curved object holder in accordance with the present invention;

FIG. 7 is a side perspective view of the curved object holder in accordance with the present invention; and,

FIG. 8 is a front perspective view of the curved object holder in accordance with the present invention.

1 Claim, 6 Drawing Sheets
